MIXING NOZZLE

Robert M. Doull, Westmount, Quebec, Canada

Application April 10, 1946, Serial No. 661,027

5 Claims. (Cl. 91—44)

1

This invention relates to mixing nozzles and particularly to cement gun mixing nozzles through which a pneumatically propelled stream of a hydrated mixture of sand and cement is directed at high velocity to form a dense, adherent, cementitious mass on walls or other surfaces being constructed, repaired or strengthened.

Economical use of the well-known cement gun apparatus for efficiently constructing, repairing or strengthening walls or other surfaces is largely dependent on efficient mixing and hydration of the pneumatically propelled sand and cement aggregate during its rapid travel through the relatively short mixing nozzle from which the stream of hydrated material is projected against the surface being treated. Insufficient mixing and hydration of the aggregate during its passage through the mixing nozzle results in (a) excessive spreading of the stream as it leaves the nozzle, resulting in loss of cement and fine sand particles which are blown away and wasted by the escaping compressed air and (b) excessive rebounding of relatively dry particles of the stream from the surface being treated which substantially increases the waste of material and also interferes with the rapid and efficient formation of the desired dense cementitious mass on said surface.

With the foregoing in mind, various improved types of cement gun nozzles, designed to reduce "spreading" and "rebound," have been proposed and adopted but, even with the use of the best nozzle designs now available, waste of materials and other difficulties due to excessive "spreading" and "rebound" is still a serious factor.

According to the present invention, "spreading" and "rebound" are reduced to a much greater extent than heretofore by the provision of a nozzle having a substantially zigzag form of mixing passage which varies in cross sectional area so that the stream of material passing therethrough is caused to change its direction of flow and is expanded and then contracted in a manner which ensures a more thorough mixing and hydration of the sand and cement aggregate.

A preferred embodiment of the invention is illustrated in the accompanying drawings, in which—

Fig. 1 is a perspective view of my improved mixing nozzle.

Fig. 2 is an end view of said nozzle as it appears when looking toward the discharge end.

Fig. 3 is a longitudinal sectional view of the nozzle showing it connected to a conventional water ring and supply hose through which sand,

2

cement and water are supplied to the delivery end of the nozzle.

Figs. 4 and 5 are plan views of two nozzle sections which are assembled with each other to form the complete nozzle shown in the preceding figures.

As shown in these drawings, my improved nozzle comprises full length half-sections 5 and 6 formed with straight longitudinal side edges 7 and laterally projecting fastening lugs 8. These nozzle sections are assembled, as shown in Figs. 1 to 3 inclusive, with their longitudinal side edges 7 butted together and the lugs 8 of one section fastened to corresponding lugs 8 of the companion section by bolts 9 and clamping nuts 10.

Each nozzle section comprises end portions 11 and 12 of substantially semi-circular cross section and an intermediate portion 13 which is substantially U shaped in cross section. The semi-circular end portion 11 of nozzle section 5 is longer and of smaller radius compared with the end portion 12. The semi-circular end portion 11 of nozzle section 6 is longer and of greater radius compared with the end portion 12. The intermediate U shaped portion 13 of each nozzle section gradually diminishes in depth toward the end portions 11 and 12 and has a maximum depth substantially greater than the depth of said end portions. As shown in Figs. 4 and 5, each half section of the nozzle is longitudinally tapered so that it gradually diminishes in width toward one end. In this connection it will be noted that nozzle section 5 diminishes in width toward its end portion 11 while nozzle section 6 diminishes in width toward its end portion 12.

The nozzle sections 5 and 6 are secured together, with the relatively long end portion 11 of one section, opposed to the relatively short end portion 12 of the other section. This results in the U shaped intermediate portions 13 of the nozzle sections being offset relatively to each other in the longitudinal direction of the nozzle so that the intermediate portion 13 of each nozzle is opposed to part of the end portion 11 and part of the intermediate portion 13 of the companion section. The effect of this is to provide the nozzle with a flow passage having an intermediate bend of varying cross sectional area designed to change the direction of flow and to expand and then contract a stream of material passing from the inlet end A to the discharge end B of the nozzle.

The intermediate bend portion of the nozzle passage may be regarded as that portion which lies between the relatively short end portion 12

of nozzle section 5 and the relatively short end portion 12 of nozzle section 6. This intermediate bend portion of the nozzle passage includes a central zone C of maximum cross sectional area, and end zones D and D' of gradually diminishing cross sectional area toward the ends of the nozzle. The end zone D diminishes in area toward and merges with a cylindrical inlet zone E extending to the inlet end A of the nozzle. The zone D' diminishes in area toward and merges with a cylindrical discharge zone F extending to the discharge end B of the nozzle in alignment with the inlet zone E.

The sand and cement are delivered to the inlet zone E of the nozzle passage through a conventional water ring 16 coupling the inlet end of the nozzle to the sand and cement supply hose 17 through which the sand and cement are pneumatically propelled at high velocity. The water ring is provided with the usual water passages 18 through which water is added to the sand and cement entering the nozzle inlet zone E. As the stream of material passes from inlet zone E, through the zones D, C and D', to the outlet zone F, it is caused to change its direction of flow. The stream of material is also permitted to expand during its passage through zones D and C but is contracted during its passage through zone D' to outlet zone F.

The turbulence resulting from the change in direction of flow of the stream as it travels from the inlet to the discharge end of the nozzle passage causes the particles of the stream to be subjected to a rolling and mixing action which enables the particles to be more intimately mixed and also ensures better hydration of the cementitious material prior to its discharge from the nozzle.

The manner in which the intermediate bend portion of the nozzle flow passage is varied in cross section in relation to the flow of material through the nozzle permits the air carrying the sand and cement particles to expand shortly after it enters the nozzle and to be compressed again before it leaves the nozzle. The net result is a thorough mechanical mixing by reason of the turbulence set up in the stream of material by the change in direction and the further agitation caused by rapidly expanding and then contracting the air carrying the aggregate particles and water toward the discharge end of the nozzle. The ultimate advantage obtained is that the stream of material leaving the nozzle exhibits a substantially reduced tendency to spread and the particles of material are more intimately mixed so that greater cohesion between the particles is obtained and this, in turn, increases the adhesion between the particles and the surfaces against which they are projecting.

The water ring 16 is screwed onto a threaded collar formed by mating externally threaded portions 12a and 11a of the nozzle sections 5 and 6.

The semi-cylindrical end portion 12 of each nozzle section has the same radius as the opposing semi-cylindrical portion 11 of the companion

nozzle section. Consequently, the inlet zone E formed by and between the opposing cylindrical end portions 11 and 12 located at the inlet end of the nozzle is of greater diameter compared with the outlet zone F formed by and between the opposing cylindrical portions 11 and 12 at the discharge end of the nozzle.

The mixing passage defining surfaces of the metal nozzle sections are protected by a rubber lining 20, preferably moulded in one piece shaped to fit the nozzle sections.

I claim:

1. A mixing nozzle of the kind described comprising two full length casing sections formed with straight longitudinal side edges butted together, each section comprising end portions of unequal length and an intermediate portion having a maximum depth greater than the maximum depth of the end portions, said sections being butted together with the shorter end portion of each section opposed to the longer end portion of the companion section and with the said intermediate portions of the sections staggered longitudinally of the nozzle.

2. A mixing nozzle as set forth in claim 1, in which the end portions of each section are semi-circular in cross section and in which the intermediate portion of each section is substantially U-shaped in cross section.

3. A mixing nozzle as set forth in claim 1, in which the opposite end portions of each section are semi-circular in cross section and in which the shorter end portion of one section has a greater radius than the longer end portion while the shorter end portion of the companion section has a smaller radius than the longer end portion, the radius of each end portion of each section being the same as that of the opposing end portion of the companion section.

4. A mixing nozzle as set forth in claim 1, in which the intermediate portion of each section gradually diminishes in depth toward the end portions.

5. A mixing nozzle as set forth in claim 1, in which the end portions of each section are semi-circular in cross section and are aligned with each other and in which the intermediate portion of each section is substantially U-shaped in cross section and gradually diminishes in depth toward the end portions.
